P. H. Jackson,

Windlass.

No 36,006.

Patented July 29, 1862.

UNITED STATES PATENT OFFICE.

PETER H. JACKSON, OF NEW YORK, N. Y.

IMPROVED VERTICAL WINDLASSES.

Specification forming part of Letters Patent No. **36,006**, dated July 29, 1862.

To all whom it may concern:

Be it known that I, PETER H. JACKSON, of the city and State of New York, have invented, made, and applied to use a certain new and useful Improvement in Vertical Windlasses; and I do hereby declare that the following is a full, clear, and exact description of my said invention, reference being had to the annexed drawings, making part of this specification, wherein—

Figure 1 is a plan of my windlass, and Fig. 2 is a vertical section of the same.

Similar marks of reference denote the same parts.

My invention is an improvement upon that for which Letters Patent were granted to me April 1, 1862; and it consists in an improved means for stopping the chain-barrel, so as to check the chain as given out, or hold the same rigidly while the vessel is riding at anchor.

In the drawings, *a* is a cast-iron box containing a gear-wheel connecting the shaft *b* to the gear-wheel *c*, Fig. 2, that is on a vertical stud, *d*, and said wheel *c* is provided with a long hub, receiving the power-capstan *e* at its upper end, and below the capstan *e*, between that and the top of the box *a*, is the chain-wheel *f*, formed with indentations corresponding to the chain to be acted on, and the capstan *e* and chain-wheel *f* are moved in either direction by a capstan or capstan-head applied to the vertical shaft *b* in the manner specified in my aforesaid Letters Patent, and the capstan *e* and chain-wheel *f* are connected to each other, when desired, by keys 1 1, inserted in mortises formed by grooves in the contiguous faces of the wheel *f* and base of the capstan *e*, and said keys, when inserted, are held in place by pins 2 2, introduced through holes in the base of the capstan, as shown in Fig. 2.

My improved mechanism for stopping the chain-barrel consists of a fixed lug, *i*, cast on or affixed to the upper plate of the box *a*, and the shape and position of this lug is such that the chain-wheel *f*, when moving with the wheel *c*, does not touch against the same. On the opposite side of the chain-wheel to the said lug *i* is a friction-clamp, *k*, set to slide in a seat formed in the top of the said box *a*, and a bolt, 3, is provided, passing through a slot in said clamp to hold the same down to its

place. The said clamp *k* has a mortise through it, as seen by dotted lines in Fig. 1, and in this mortise an eccentric, *o*, is placed, that is set on a pin or bolt, 4, and provided with a lever-handle, *l*, by which said eccentric can be revolved on the said bolt 4, and by its action in the slot or mortise in the friction-clamp *k* cause the end of said clamp to press tightly against the edge of the chain-wheel *f*.

It will now be evident that if a slight play is left of the chain-wheel *f* on its hub the action of the friction-clamp will be to relieve said hub and shaft from all strain, because the said clamp, acting on the side where the chain cable passes away, receives the strain due to said chain and binds the wheel firmly by friction between the end of said clamp and the block *i*, pressing the heaver away from the shaft and preventing any more chain running out until the said clamp is liberated. By this means I am able to use my chain-wheel as a cable-stopper, if necessary, and regulate the speed with which the chain is allowed to run out. If the end of the friction-clamp *k* is formed with a projection taking a depression in the edge of the chain-wheel, the stopping of the chain-wheel will be more sudden and reliable, although such a device will not generally be required.

The lever *l*, that operates on the eccentric *o*, may be secured firmly in position after the chain has been entirely stopped, so that the vessel can ride at anchor with the chain cable around the chain-wheel with perfect safety.

The end of the friction-clamp *k* should be inclined, as shown at 5, in order that it may overhang the edge of the chain-wheel and tend to press the same down upon the upper surface of the box *a* and increase the friction, and the lug *i* may be made also to overhang said edge in a similar manner, to keep the wheel down against the chain, if that is inclined upward.

What I claim, and desire to secure by Letters Patent, is—

1. The friction-clamp *k*, actuated by the eccentric *o*, in combination with the lug *i*, to clamp and arrest the movement of the wheel *f*, substantially as and for the purposes specified.

2. The overhanging end 5, in combination

with the clamp *k*, wheel *f*, and box *a*, as specified, to press the said chain-wheel to the top of the box *a* and increase the friction, as set forth.

3. The pins 2, introduced through the base of the capstan *e*, and keys 1, in combination with the said heaver *f*, to hold said keys in place, as set forth.

In witness whereof I have hereunto set my signature this 17th of May, 1862.

PETER H. JACKSON.
